UNITED STATES PATENT OFFICE

DAVID CHRISTIAAN HENNY, OF PORTLAND, OREGON

CONCRETE DAM

Application filed September 21, 1932. Serial No. 634,098.

My invention relates to concrete dams in which serrated contraction joints are introduced at the desired places.

The objects of my invention are to render 5 innocuous the detrimental effects of contraction and expansion in concrete dams; to restrict the unavoidable effects of contraction and expansion as much as possible to definite and predetermined planes; to stop 10 the formation of shrinkage cracks; to prevent the failure of dams as caused by the haphazard formation of a certain kind of shrinkage cracks; and to give the contraction joints a form which utilizes the full cross- 15 sectional surface of the concrete in compression.

Other objects and advantages are to be found in the construction and arrangement of parts, as will be described in the specification, and particularly pointed out in the 20 appended claims.

I attain these objects with the mechanism illustrated in the accompanying drawings, in which:

25 Fig. 1 is a vertical cross-section of a gravity dam or a gravity arch dam.

Fig. 2 is a cross-sectional elevation of a buttress-supported dam.

Fig. 3 is a detail of the contraction joint.

30 Fig. 4 is a plan view of the arch dam.

Similar numerals refer to similar parts throughout the several views.

In structures as exemplified by Fig. 1, the

35 principal direction of stresses is as indicated by the arrow 1. It is obvious that a shrink-

age crack—especially one that is more or less straight and flat—in the direction of the

arrow 2 would affect the equilibrium of a dam very materially, and by permitting the

40 two concrete surfaces of the crack to slide upon each other lead to a failure of the dam.

To overcome any danger threatening from this source, I introduce a serrated contraction joint whose general plane and direction

45 conform to the one indicated by the arrow 2.

As particularly illustrated in Fig. 3, those

50 contact surfaces 3 which are under compression are held normal to the direction of principal stresses 1, while the immediately ad-

the direction of principal stress 1, and are consequently located in a plane of no shear. In this way any sliding of the two separated concrete masses upon each other is prevented, yet, for compression purposes, the full cross- 55 sectional area of the mass is retained. Furthermore, the introduction of these contraction joints with the consequent separation of a large mass of concrete prevents the development of dangerous shrinkage cracks 60 at intermediate points.

In Fig. 2 the direction of the serrated contact planes is also alternately normal and parallel to the direction of principal stresses 5 in the buttress 6 where the general plane 65 of the contraction joint is indicated by the arrow 7.

In Fig. 4, which refers to arch dams, the principal arch stress would not be directed more or less vertically toward the base, as 70 shown in Figs. 1 and 2, but, rather, more or less horizontally toward the abutments as indicated by the arrow 8. In such dams, contraction joints are usually made radial.

It may be desirable, for important construc- 75 tional reasons, for one or more of such joints in an arch dam to deviate from the radial direction as indicated by the arrow 9. A joint thus deviating if made substantially flat or even if provided with usual interlocking 80

keys, will be essentially weak for the purpose of resisting shear and for transmitting arch compression stresses. By introducing in such joints serrations substantially vertical, and having planes alternately substantially 85 normal and parallel to the principal stress, as referred to in the description of Figs. 1 and 2, I attain a joint which is, in all respects, as strong as a radial joint.

Only one contraction joint is shown in each 90 type of dam to illustrate the principle of my invention. It is, of course, obvious that a plurality of joints must be employed where the magnitude or nature of the dam demands it.

Having thus described my invention, it will 95 be seen that my objects have been accomplished, and though I have showed the preferred form of construction, I reserve to myself the right to make minor changes provid- 100

ing I do not contravene the spirit and principle of my invention.

I claim:

1. In a concrete dam serrated contraction joints extending in a substantially vertical plane with the contacting surfaces thereof being alternately substantially normal and parallel to the direction of principal stresses.
2. In a concrete dam of the arch type serrated contraction joints extending in a substantially vertical plane deviating from a radial direction with the contacting surfaces thereof being alternately substantially normal and parallel to the direction of arch stresses.
3. In a concrete dam of the gravity or combined gravity and arch type serrated contraction joints extending in a substantially vertical plane with the contacting surfaces thereof being substantially normal and parallel to the direction of principal stresses in an up and down-stream direction.

In testimony whereof I affix my signature.
